CLAIM

We claim the ornamental design for a vacuum-insulated glass plate, as shown and described.

DESCRIPTION

FIG. 1 is a front view of a vacuum-insulated glass plate according to the first embodiment of the present invention, the rear view being a mirror image thereof;

FIG. 2 is a left side view thereof, the right side view being a mirror image thereof;

FIG. 3 is a top view thereof, the bottom view being a mirror image thereof;

FIG. 4 is an enlarged view of the section taken along lines 4-4 in FIG. 1;

FIG. 5 is a cross-sectional view taken long line 5-5 in FIG. 4;

FIG. 6 is a front view of a vacuum-insulated glass plate according to the second embodiment of the present invention, the rear view being a mirror image thereof;

FIG. 7 is a left side view thereof, the right side view being a mirror image thereof;

FIG. 8 is a top view hereof, the bottom view being a mirror image thereof;

(Continued)

FIG. 9 is an enlarged view of the section taken along lines 9-9 in FIG. 6; and,
 FIG. 10 is a cross-sectional view taken long line 10-10 in FIG. 9.

The broken lines in FIGS. 4, 5, 9 and 10 represent the line where the cross-section was cut away and form no part of the claim.
